UNITED STATES PATENT OFFICE.

GEORGE E. SHIPPEY, OF PITTSFIELD, MASSACHUSETTS.

SHOCK-ABSORBER FOR SPRING-VEHICLES.

No. 825,083.

Specification of Letters Patent.

Patented July 3, 1906.

Application filed November 8, 1905. Serial No. 286,414.

To all whom it may concern:

Be it known that I, GEORGE E. SHIPPEY, a citizen of the United States, residing at Pittsfield, in the county of Berkshire and 5 Commonwealth of Massachusetts, have invented new and useful Improvements in Shock-Absorbers for Spring-Vehicles, of which the following is a full and complete specification, such as will enable those skilled 10 in the art to which it appertains to make and use the same.

This invention relates to shock-absorbers; and one object thereof is to provide an improved device which may be attached to a 15 spring-vehicle, between the parts thereof, in such manner that the normal agitation of the superposed carriage and all sudden and violent jolting thereof resulting from rough travel is retarded and absorbed thereby; and 20 with this and other objects in view my invention consists in certain features of construction and arrangement of parts, as hereinafter described, and indicated in the claims.

Reference is to be had to the accompanying 25 drawings, forming a part of this specification, in which corresponding parts are indicated by similar reference characters in each of the views.

Figure 1 is a side view of sections of a 30 spring-vehicle with a shock-absorber constructed according to my invention and attached thereto; Fig. 2, a perspective edge view of the parts shown in Fig. 1 on a slightly reduced scale; Fig. 3, a top view of the roller-holder H on the scale of Fig. 1.

Referring to the drawings, let F indicate 35 a cross-section of the axle of a vehicle of any approved construction; D, a section of a series of parallel flat springs laid crosswise upon the axle F on either side of the vehicle, said springs forming an elastic connection 40 between the underbody or progressive portion of the vehicle and the superposed carriage movable relatively thereto; G, clamps secured to the axle F and holding the springs 45 in position thereon; C, a section of the framework of the superposed carriage movably supported upon springs D. These parts 50 may be of any suitable construction or material.

A represents a wedge-spring, preferably 55 constructed of a flat metallic strip of spring-steel or other suitable material, bent centrally at point a², forming a U-shaped figure, one end thereof a⁴ being turned inwardly at right angles at the point a³ and adapted

to bear movably against the opposite end of the strip at the point a¹. Said opposite end a⁵ of the strip forms an elongated neck or shank provided at its extremity with a perforation consisting, preferably, of one or more round holes spaced apart or an elongated slot containing lateral notches for the introduction of a bolt or rivet E, by which the spring A is laterally secured to the frame C 60 and suspended therefrom, said bolt E further serving as a pivot for the spring A, affording means for a lateral movement thereof for adjustment within the antifriction-rollers B.

The sides of the spring A are made elliptical, with their crowned centers turned inward, forming a double-wedged spring, and are adapted to bear movably against the compression antifriction-rollers B, placed centrally on either side thereof. Said antifriction-rollers consist of metallic cylinders 70 movably mounted upon parallel bearing-pins b, secured at either end in the sides or plates h of the holder H, said pins having their ends riveted in perforations provided 75 for their reception in said plates h and being rigidly secured thereto in stationary positions.

H represents the holder provided for the support of the bearing-pins b and antifriction-rollers B mounted thereon, and is preferably constructed of sheet metal formed as shown in Fig. 3, and consists of two parallel side plates h of uniform dimensions spaced apart for the reception of the antifriction-rollers B and held rigidly in position relatively to each other by a base-plate h², preferably forming an integral part therewith. Said holder H is further provided with a flat shank or handle plate h¹, projected outwardly 90 at right angles from the extended end of one of the side plates h, at the top thereof, preferably forming an integral part therewith. The holder H is rigidly secured in a stationary position to the underbody of the vehicle 95 for coöperation with the spring A by the introduction of the shank h¹ between the axle F and the carriage-springs D clamped theron, that portion of the holder which supports the antifriction-rollers B extending laterally 100 away from the springs D at a sufficient distance therefrom to allow free clearance for the respective movements of springs A and D.

The operation of my device is as follows: 110 The depression of the movable carriage-frame C under load strain, accelerated by a

violent jolt or shock resulting from rough travel, forces the wedge-spring A downward between the antifriction-rollers B, compressing the divergent sides of the said spring, which are prevented from actual compact by the intercepting end a^4 of one of them, closer together. The compression of the spring A between the rollers B, as described, forms thus a cushioned resistance to the downward movement of the superposed carriage of the vehicle, the resistance being graduated increasingly to the extent of the force of the downward movement until the latter is overcome and the carriage brought to rest. The elevation of the frame C or recoil thereof due to the responsive action of the resilient springs D, upon which it is supported, reverses the operation previously described, compressing the lower portion of the wedge-spring A between the antifriction-rollers B in a similar manner and with like effect. These operations are continued alternately until the force actuating said wedge-spring is wholly expended and absorbed by means of my device, when the movable carriage is brought to a state of rest.

It will be apparent that the size and strength of the parts composing my device are proportioned to the weight and use of the vehicle to which it is applied, while slight modifications of the preferred form of their construction described in these specifications may be made without changing their several functions or departing from the spirit of my invention.

Having fully described my invention, I claim as new and desire to secure by Letters Patent—

1. In a vehicle, comprising a progressive underbody and a superposed part movably supported thereon, mechanical means providing a retarding effect upon the vertical movements of the said superposed part; said means comprising rollers adapted to compress intercepting resilient springs moving relatively thereto.

2. In vehicles, retarding mechanism comprising a resilient wedge-shaped spring, A, compression-rollers, B, a holder, H, supporting said rollers in stationary, parallel position, and means for operating said spring longitudinally between said rollers, for the purpose described.

3. In a vehicle, in combination with a progressive underbody and a superposed part movably supported thereon, mechanical retarding means providing a yielding and grad-

ually-increasing resistance to movements of the said superposed part of the vehicle; said means comprising a reciprocally-acting double-wedge-shaped spring coöperating with stationary rollers compressing said spring centrally.

4. In retarding mechanism providing resistance to the movements of the superposed part of vehicles of the character described, the combination of compression-rollers, B, a resilient double-wedge-shaped spring, A, intercepting said rollers, means for supporting said parts in relative position and means for actuating said spring longitudinally within said rollers.

5. In a vehicle, the combination with a progressive underbody thereof, a superposed carriage supported thereon and movable relatively thereto, and interposed spring connection, of double-wedge-shaped springs, A, actuated vertically by the said superposed carriage, provided with an extended shank, a^5 , and suspended laterally from the frame C of the said carriage, a bolt E securing the springs A to the said frame C, passed through said frame and the shank a^5 of said springs A, parallel antifriction-rollers B compressing said springs A laterally and mounted upon bearing-pins b, stationary bearing-pins b holding the said antifriction-rollers B in position relatively to the springs A and securely attached to a holder, H, provided therefor, and a holder H supporting the bearing-pins b and rollers B mounted thereon, comprising parallel side plates h intercepted by bearing-pins b and containing perforations for the introduction of said bearing-pins, a base-plate h^2 connecting and securely attached to said side plates h, and a shank or handle h' rigidly attached to the extended end of one of said side plates, h, and projected outwardly at right angles therefrom; said holder H being held in rigid position relatively to springs A by the introduction of the shank h' thereof between the axle, F, of the said underbody of the vehicle and springs D secured thereon by clamps G, substantially as described and for the purpose set forth.

In testimony that I claim the foregoing as my invention I have hereunto signed my name, in the presence of the subscribing witnesses, this 7th day of November, A. D. 1905.

GEORGE E. SHIPPEY.
